UNITED STATES PATENT OFFICE.

ANDREW STARK, OF CHICAGO, ILLINOIS.

RAIL-ANCHOR.

1,172,496.

Specification of Letters Patent. Patented Feb. 22, 1916.

Application filed July 26, 1915. Serial No. 41,809.

To all whom it may concern:

Be it known that I, ANDREW STARK, a citizen of the United States, residing at Chicago, in the county of Cook and State of Illinois, have invented certain new and useful Improvements in Rail-Anchors, of which the following is a specification, reference being had to the accompanying drawings, forming a part thereof.

The purpose of this invention is to provide a device of the class known as rail anchors designed to be attached to railway rails and to abut the cross tie for preventing longitudinal creeping of the rails.

It consists of the features and elements described and shown in the drawings as indicated by the claims.

In the drawings: Figure 1 is a top plan view partially in section of a device embodying this invention, the outlines of the rail and cross tie being shown in dotted lines. Fig. 2 is a bottom plan view of the device shown in Fig. 1. Fig. 3 is a top plan view of the device with the wedge member removed and with the gripping members positioned for removal from the rail. Fig. 4 is a section taken longitudinally of the rail as indicated at line 4—4 on Fig. 1. Fig. 5 is a section taken transversely of the rail as indicated at line 5—5 on Fig. 1.

The device illustrated in the drawings is a three-piece construction composed of two gripping members, A and B, respectively, and a wedge member, C. The gripping member, A, is formed with hooks, A¹ and A², at its opposite ends respectively, extending above its flat surfaces, A³, and opening toward each other. The middle portion, A⁴, of the upper surface of the member, A, is depressed below the plane of the portions, A³, A³, and formed with a pivot stud or boss, A⁵, to receive the middle portion of the member, B, which is apertured for the purpose at B¹. When the parts, A and B, are thus assembled with the pivot, A⁵, engaging the aperture, B¹, the flat areas, B³, of the member, B, will lie in about the same plane as the areas, A³, A³, of the member, A; but the member, B, also has a depressed middle area, B⁴, and its ends are formed as upwardly extending and opposing hooks, B⁵, and B⁶, respectively. With the member, B, thus crossed over the member, A, the device is applied to the rails so as to bring the

surfaces, A³ and B³, into contact with the under surface of the rail flange. The overhanging terminals of the hooks, A² and B⁶, are slanted off at A¹² and B¹⁶, so as to be alined with each other when the members, A and B, are swung together about their pivot to their position of least angular divergence. In this position the distance between the hooks, A¹ and B⁵, and the hooks, A² and B⁶, is a maximum and is sufficient to permit the former pair of hooks to be engaged with one edge of the rail flange while the latter pair are swung upward past the opposite edge of the flange to bring the areas, A³ and B³, into contact with the under surface of the rail. Then by opening out the members, A and B, to the position shown in Fig. 1, the hooks, A² and B⁶, will also engage the rail flange causing the device as a whole to hang in place on the rail. The depression at B⁴, in the member, B, now provides space for the insertion of the wedge, C. The areas, A³ and B³, of the gripping members are each partially bounded by the curved outline of the shoulders, A¹³ and B¹³, which are positioned for contact with the diverging lateral edges, C¹, of the wedge, C, as the latter is inserted in the device. The curves of these shoulders are so formed that all four of the shoulders will remain in contact with the straight but diverging edges, C¹, of the wedge, C, at the successive positions of the latter as it is driven farther and farther into place, though it will be evident that such inward movement of the wedge will cause the gripping members, A and B, to swing open more widely, increasing the distance between the hooks, A¹ and B⁵, or between the hooks, A² and B⁶, or even between both pairs of hooks. To permit this action the aperture, B¹, is made considerably larger than the pivot stud, A⁵, so that the wedge, C, and not the pivotal connection controls the movement and position of the gripping members. It will be evident that this implies that the curved vertical walls, A^x and B^x, of the hook portions constitute temporary and shifting fulcrums for the angular movements of the gripping members, A and B, as they adjust themselves to successive positions of the entering wedge member, C. Thus as the wedge, C, is driven into place the gripping bars, A and B, open up with

respect to the wedge but close upon the rail, the hooks, A² and B⁵, approaching each other as they are pushed farther and farther from the hooks, B⁶ and A¹, respectively.

5 The depth or thickness of the wedge member, C, in a vertical direction is approximately the depth of the depression at, B⁴, in the gripping member, B, and may be substantially uniform throughout the length of 10 the wedge except that its tip, C², may be tapered or beveled to a fairly thin edge to facilitate entering it. However, it is desirable that as the gripping surfaces, A^x and B^x, on the hooks approach their final position 15 on the rail the inner or downwardly facing surfaces of the hook terminals may also come into strong frictional contact with the rail flange. To insure this the lateral edges, C¹, of the wedge member, C, are 20 slightly undercut or beveled so that the wedge is somewhat wider at its top surface than at its bottom, and the curved shoulders, A¹³ and B¹³, are correspondingly beveled to form sloping faces for the sides of 25 the wedge, C, so that as it approaches its final position of maximum tightness the wedge tends to rise out of the groove into which it is driven up against the under surface of the rail flange, thus causing the 30 hook terminals on the gripping members, A and B, to react strongly upon the upper surface of the rail flange, and producing a final engagement of the device with the rail in which the rail flange is gripped both vertically and transversely and itself frictionally 35 engages not only the gripping members, A and B, but also the wedge, C, at its upper surface. The wedge may be made of rolled steel or as a malleable casting, so that when 40 it has been driven to this final position its tip or point, C², may be bent up around the edge of the rail flange so as to effectually prevent the wedge from working loose.

Looking at the under side of the device, it 45 will be seen that except at their lapped middle portions both of the gripping bars, A and B, are formed with vertically disposed stiffening ribs, A^y and B^y, respectively, which extend up around the hooked ends of 50 the members for strengthening these portions. One of these ribs on the bar, A, is enlarged into a considerable flange, A^z, designed to abut the vertical surface of the cross tie directly ahead of the device to render 55 the latter effective for its purpose, namely, preventing creeping of the rail. This flange is reinforced by a stiffening rib or brace, A⁶. The wedge, C, is formed with a downwardly extending head portion, C³, which presents a larger area for driving and which when the wedge is driven home to its 60 final position aligns approximately with the bracing rib, A⁶, so that any stress against the flange, A^z, caused by the tendency of 65 the rail to creep longitudinally is transmit-

ted compressively through the brace, A^z, and the head, C³, to the gripping member, B at B⁵. It is not expected that such stress will cause any relative movement among the three parts of the device, but that being 70 clamped to the rail as above described the three members, A, B and C, will act simply as a unit, gripping the rail and constituting a lug or abutment thereon which will engage the cross tie and prevent the rail from 75 moving over the tie.

It may be noted that the nature of this device makes it possible for one size of gripping bars, A and B, to serve on any one of 80 two or three sizes of rail simply by the provision of different wedges, C, of various widths. Within certain limits the gripping bars may be effectively engaged with the rail flange at various angles, and their range of 85 angular movement for engagement or disengagement may be shifted to different parts of their total range of movement simply by the use of such differing sizes of wedges, C. This coupled with the fact that the accommodation of the vertical wedging to the 90 horizontal wedging action as above described renders all machining unnecessary, making it possible to use simple casting for all parts, makes the device a comparatively 95 inexpensive fixture.

I claim:

1. A rail anchor comprising a pair of gripping bars having ends formed for gripping one edge of the rail flange, said bars extending in oppositely oblique directions 100 transversely of the rail, means adapted to grip the other edge of the rail flange, and spreading means accommodated between the aforesaid ends of the bars adapted to force them apart longitudinally of the rail for 105 tightening their grip thereon.

2. A rail anchor comprising a pair of gripping bars having ends formed for engaging one edge of the rail flange, said bars being connected and extending in oppositely 110 diagonal directions transversely of the rail, means for engaging the other edge of the rail flange, and a wedge adapted to be driven between the diverging ends of said bars in horizontal direction transversely of the rail. 115

3. A rail anchor comprising a pair of gripping bars having hooked ends for engaging one edge of the rail flange, said bars being connected and extending in oppositely 120 diagonal directions transversely of the rail, hooked means for engaging the other edge of the rail flange, and a wedge adapted to be driven between the diverging ends of said bars in horizontal direction transversely of the rail. 125

4. A rail anchor comprising a pair of gripping bars each having both ends formed for engaging the opposite edges of the rail flange, said bars being lapped one upon the other to extend in oppositely diagonal directions 130

- under the rail, a loose pivotal connection between said bars, and means for spreading the ends of said bars at each edge of the rail flange for tightening the grip of the bars upon said flange.
5. A rail anchor comprising a pair of gripper bars each having both ends formed for engaging the opposite edges of the rail flange, said bars being lapped one upon the other to extend in oppositely diagonal directions under the rail, and spreading means accommodated between the bars at both edges of the rail flange adapted to simultaneously force them apart longitudinally of the rail for tightening their grip thereon.
10. A rail anchor comprising a pair of gripper bars each having both ends formed for engaging the opposite edges of the rail flange, and said bars being lapped one upon the other to extend in oppositely diagonal directions under the rail, and a wedge adapted to be driven transversely of the rail in horizontal direction and to contact simultaneously with the diverging bars at both sides of said rail for increasing their divergence and tightening their grip upon said rail flange.
15. A rail anchor comprising a pair of gripper bars each having both ends hooked for engaging the opposite edges of the rail flange, said bars being lapped one upon the other to extend in oppositely diagonal directions under the rail, and a wedge adapted to be driven between the diverging end of said bars in horizontal direction transversely of the rail, said wedge being accommodated between the bars and the under surface of the rail flange, the tapering edges of said wedge being beveled diverging upwardly, and the surfaces of the bars being correspondingly beveled to engage said edges flatwise so that the driving of the wedge tends to crowd it up against the rail flange and to draw the hooked ends of the bars down on to said flange.
20. A rail anchor comprising a pair of gripper bars each having both ends formed for engaging the opposite edges of the rail flange, and said bars being lapped one upon the other to extend in oppositely diagonal directions under the rail, and a wedge adapted to be driven between the diverging ends of said bars transversely of the rail and immediately under the flange thereof, such wedge and gripper bars having coöperating beveled surfaces which when engaged as the wedge is driven tend to force said wedge against the under surface of the rail flange.
25. A rail anchor comprising a pair of gripper bars each having both ends formed for engaging the opposite edges of the rail flange, and said bars being lapped one upon the other to extend in oppositely diagonal directions under the rail, and a wedge adapted to be driven between the diverging ends of said bars transversely of the rail and immediately under the flange thereof, such wedge and gripper bars having coöperating beveled surfaces which when engaged as the wedge is driven tend to force said wedge against the under surface of the rail flange.
30. A rail anchor comprising a pair of gripper bars each having both ends hooked for engaging the opposite edges of the rail flange, and said bars being lapped one upon the other to extend in oppositely diagonal directions under the rail, and a wedge adapted to be driven between the diverging end of said bars in horizontal direction transversely of the rail, said wedge being accommodated between the bars and the under surface of the rail flange, the tapering edges of said wedge being beveled diverging upwardly, and the surfaces of the bars being correspondingly beveled to engage said edges flatwise so that the driving of the wedge tends to crowd it up against the rail flange and to draw the hooked ends of the bars down on to said flange.
35. A rail anchor comprising a pair of gripper bars each having both ends formed for engaging the opposite edges of the rail flange, and said bars being lapped one upon the other to extend in oppositely diagonal directions under the rail, and a wedge adapted to be driven between the diverging ends of said bars transversely of the rail and immediately under the flange thereof, such wedge and gripper bars having coöperating beveled surfaces which when engaged as the wedge is driven tend to force said wedge against the under surface of the rail flange.
40. A rail anchor comprising a pair of gripper bars each having both ends formed for engaging the opposite edges of the rail flange, and said bars being lapped one upon the other between their ends so as to extend in oppositely diagonal directions under the rail, both bars having areas at both sides of their lapped portions lying approximately in the plane of the under side of the rail flange, each of said areas being partially bounded by curved shoulders, such shoulders of one bar opposing the respective shoulder of the other bar, and a wedge adapted to lie upon the lapped portion of said bars directly under the rail flange and between said opposing shoulders of the bars, with each of the tapering edges simultaneously engaging two of said shoulders, so that driving the wedge transversely of the rail in horizontal direction operates to

spread the ends of the bars at both edges of the rail flange for tightening the grip of said bars upon the flange.

9. A rail anchor comprising a pair of gripper bars having hooked ends for engaging one edge of the rail flange, said bars being connected and extending in oppositely diagonal directions transversely of the rail, means for engaging the other edge of the rail flange, and a wedge adapted to be driven between the diverging ends of said bars in horizontal direction transversely of the rail, said wedge being accommodated between the bars and the under surface of the rail flange, the edges of said wedge being beveled diverging upwardly and the surface of the bars being correspondingly beveled to engage the said edges flatwise for crowding the hooked ends of the bars against the rail flange.

10. In a rail anchor comprising members formed to engage the edges and top surfaces of the rail flange and having portions extending across the rail under said flange, a wedge adapted to be driven horizontally between said portions and said flange, the tapering edges of said wedge being beveled diverging upwardly, and the gripping members having correspondingly beveled faces for contact with said edges to cause the wedge to crowd up against the rail flange for drawing the members into engagement with the top surfaces thereof.

11. In a rail anchor comprising gripping bars having ends formed for engaging one edge of the rail flange, said bars being connected and extending in opposite diagonal directions transversely of the rail, means for engaging the other edge of the rail flange, and a wedge adapted to be driven between the diverging ends of said bars transversely of the rail and immediately under the flange thereof, such wedge and gripper bars having coöperating beveled surfaces which when engaged as the wedge is driven tend to force said wedge against the under surface of the rail flange.

12. In a rail anchor comprising gripping members formed to engage the edges and top surfaces of the rail flange, means arranged to react between said members and said rail flange comprising a wedge to be driven transversely of the rail between said members and the bottom flange for simultaneously forcing the members into engagement with the edges of the flange and crowding them into frictional contact with the top surfaces of said flange.

13. In a rail anchor comprising gripping members formed to engage the edges and top surfaces of the rail flange, means arranged to react between said members and said rail flange comprising a wedge to be driven transversely of the rail between said members and the bottom flange for simul-

taneously forcing the members into engagement with the edges of the flange and crowding them into frictional contact with the top surfaces of said flange, the small end of the 5 wedge being adapted to be clenched around the edge of said flange.

14. A rail anchor comprising a pair of gripper bars having ends formed for engaging one edge of the rail flange, said bars 10 being connected and extending in oppositely diagonal directions transversely of the rail, means for engaging the other edge of the rail flange and a wedge adapted to be driven between the diverging ends of said bars 15 horizontally under the rail, the entering end of said wedge being dimensioned to extend beyond the other edge of the rail flange and adapted to be bent up around the flange to retain the wedge in position.
- 20 15. A rail anchor comprising a pair of gripper bars each having both ends formed

for engaging the opposite edges of the rail flange, said bars being lapped one upon the other to extend in oppositely diagonal directions under the rail and a wedge adapted to 25 be driven transversely under the rail in horizontal direction and to contact simultaneously with the diverging bars at both sides of said rail for increasing their divergence and tightening their grip upon the rail 30 flange, the entering end of said wedge being dimensioned to extend beyond the edge of the rail flange and adapted to be bent up around said edge to retain the wedge in position.

In testimony whereof, I have hereunto set my hand at Chicago, Illinois, this 16th day of July, 1915.

ANDREW STARK.
